SHOESHINE STAND

Glen A. Smith, 4896 Rio Vista Ave.,
San Jose, Calif. 95129

Filed Sept. 25, 1969, Ser. No. 19,298

Term of patent 7 years

Int. Cl. D25—99

U.S. Cl. D13—1

FIG. 1

FIG. 2

FIG. 1 is a front elevational view of a shoeshine stand of the present invention, the sides and rear being similar in appearance;

FIG. 2 is a top view; and

FIG. 3 is a perspective view taken at an angle relative to a horizontal plane.

I claim:

The ornamental design of a shoeshine stand, substantially as shown and described.
